United States Patent Office

Des. 209,473

Patented Dec. 5, 1967

209,473

CASE FOR BEVERAGE CONTAINERS

James H. Versteeg, Middlesex, and Louis H. Peters,
Somerville, N.J., assignors to Union Carbide Cor-
poration, a corporation of New York

Filed Dec. 28, 1965, Ser. No. 350

Term of patent 14 years

(Cl. D58—5)

Fig. 1.

Fig. 2.

Fig. 3.

FIG. 4.

FIG. 5.

FIG. 1 is a top perspective view of a case for beverage containers showing our new design;

FIG. 2 is a top plan view thereof;

FIG. 3 is a bottom plan view thereof;

FIG. 4 is a modified form of the case for beverage containers of FIG. 1 wherein the top rim and corner edges are plain and devoid of ribs; and

FIG. 5 is a bottom plan view of FIG. 4.

The end and side not shown are substantially similar to the end and side shown in FIG. 1.

We claim:

The ornamental design for a case for beverage containers, as shown and described.
